UNITED STATES PATENT OFFICE.

DAVID T. GOODMAN, OF ALTOONA, PENNSYLVANIA.

HOOK.

SPECIFICATION forming part of Letters Patent No. 723,524, dated March 24, 1903.

Application filed December 2, 1902. Serial No. 133,615. (No model.)

To all whom it may concern:

Be it known that I, DAVID T. GOODMAN, a citizen of the United States, residing at Altoona, in the county of Blair, State of Pennsylvania, have invented certain new and useful Improvements in Hooks; and I do hereby declare the following to be a full, clear, and exact description of the invention, such as will enable others skilled in the art to which

it appertains to make and use the same.

This invention relates to wrecking-tackle such as is employed in wrecking operations on railways; and it has for its object to provide a hook which may be connected with the draw-head of the common form of Janney coupler to facilitate the attachment of a cable for moving the car, a further object of the invention being to provide a hook which may be easily and quickly engaged with the draw-head and which while retaining its place when subjected to strain may be readily disengaged when desired.

In the drawings forming a portion of this specification, and in which like numerals of reference indicate similar parts in the several views, Figure 1 is a perspective view showing the hook engaged with the draw-head of a coupler. Fig. 2 is a perspective view of the hook disengaged from the coupler.

Referring now to the drawings, there is shown the draw-head 5 of the well-known Janney coupler, having the slot 6 to receive a coupling-link when it is desired to connect with a common form of link-coupling and the perforations 7 to receive a coupling-pin, these perforations being formed through the laterally-projecting portions 8, upon the inner end portions of the rear faces of which are rounded lugs 9, while in the outer end portions of the rear faces are recesses 10, the lugs 9 of one draw-head being adapted for engagement with the recesses 10 of the co-operating draw-head in the manner well known to those skilled in the art.

The hook embodying the present invention comprises a stem 11, having the bill 12 at one end and the cross-bar 13 at the opposite end, the thickness of the stem being such as to permit engagement thereof in the slot 6 of

the draw-head, at which time the ends of the cross-bar 13, which project vertically above and below the stem, lie against the rear faces of the portions 8 of the draw-head, and in the front flat faces of the vertically-projecting portions of the cross-bar are recesses 14, which receive the lugs 9, so that the cross-bar is held from slipping laterally from engagement with the draw-head. The cable for moving the car is connected to the hook, and it will be seen that the greater the strain applied to the hook the more firmly will the lug 9 engage the recess 14, while as soon as the strain ceases the hook may be pressed rearwardly and then moved laterally from engagement with the draw-head.

What is claimed is—

1. A wrecking-hook comprising a stem having a bill at one end and a cross-bar at its opposite end projecting above and below the stem, said projecting portions having recesses therein.

2. A wrecking-hook comprising a stem having a bill at one end and a cross-bar at its opposite end projecting above and below the stem, said projecting portions having flat front faces having recesses therein.

3. A wrecking-hook comprising a stem having a bill at one end and a cross-bar at its opposite end projecting above and below the stem, said projecting portions having flat front faces having recesses therein adjacent to one edge of the stem.

4. A wrecking-hook comprising a stem having a bill at one end projecting laterally therefrom, and a cross-bar at its opposite end projecting in opposite directions from the stem at right angles to the direction of projection of the bill, said projecting portions of the cross-bar having flat front faces having recesses therein adjacent to one edge of the stem.

In testimony whereof I affix my signature in presence of two witnesses.

DAVID T. GOODMAN.
